JOSEPH C. HOWELL, OF FORT LEE, NEW JERSEY

ARCH SUPPORT FOR SHOES

Application filed June 24, 1932. Serial No. 619,142.

This invention relates to arch supports for the human foot and has for an object the provision of an arch support and a supporting means therefor arranged in position on the insole of a shoe, and which receives the weight of the wearer thrust upon the arch support and distributes the weight over a substantial area of the shoe sole.

Another object of the invention is the provision of an arch supporting plate, and a supporting means for the said arch supporting plate arranged on the insole of the shoe, adjacent the side edges thereof, and which at the side edges conforms to the last of the shoe.

Still another object of the invention is the provision of a spring leafed supporting means for an arch support, which will flex and bend with the movement of the sole of the shoe, will reinforce the sole of the shoe, and provide an effective means for holding the said arch support against lateral displacement in the shoe sole. The said spring leafed supporting means is particularly applicable to light weight shoes where the shoe sole does not have the necessary thickness to rigidly hold the arch support, and also may be used to advantage where the arch support is to be worn by a heavy person, so that a relatively thin shoe sole may be used.

The invention also has in view a flexible foundation for an arch support rigidly connected to the sole of the shoe in the region of the instep but unsecured at its ends, whereby it is free to flex and bend with the movement of the sole of the shoe. With these and other objects in view the invention resides in the novel features of construction and the arrangement of parts which will be more fully described and claimed hereinafter.

The invention is shown in the accompanying drawing, in which:

Figure 1 is a plan view of a shoe with a part of the shoe upper removed to show the arch supporting means in position therein and the spring leafed support therefor in dotted lines;

Fig. 2 is a longitudinal sectional view on the line 2—2 of Figure 1;

Fig. 3 is a plan view of the arch supporting means;

Fig. 4 is a plan view of the curved plate which underlies the arch supporting plate in the region of the ball of the foot;

Fig. 5 is a sectional view on the line 5—5 of Fig. 4;

Fig. 6 is a plan view of the adjustable tubular member which supports the arch supporting plate and the curved plate in position under the ball of the foot;

Fig. 7 is a cross sectional view on the line 7—7 of Fig. 6;

Fig. 8 is a cross sectional view on the line 8—8 of Fig. 3;

Fig. 9 is a plan view of the device with the arch supporting means removed;

Fig. 10 is a cross sectional view on the line 10—10 of Fig. 9 and with the arch supporting plate in position on the device; and

Fig. 11 is a perspective view of the slide plate on which one end of the spring leafed plate moves.

In the embodiment of the invention illustrated in the accompanying drawing an arch supporting plate 10 preferably co-extensive with the sole of the shoe in the region of the instep is arranged in superposed position on the inside of the shoe 11, and such plate is preferably made of flexible spring metal longitudinally arched to conform substantially to the instep of a normal foot. The said plate is adjustable in elevation toward and from the insole of the shoe at a plurality of points, two points of which may be on a transverse line in the region of the instep, under the longitudinal arches adjacent the side edges 12 and 13 of the sole 14 of the shoe. The forward edge 15 of said arch supporting plate 10 extends under the bones of the foot forming the metatarsal arch, that is, in the region of the ball of the foot, and this portion of said plate is preferably curved to define an arc of substantially a half circle, which said curved end is slotted from its forward edge inwardly as at 16, to provide a relatively flexible end portion 17. At each side of said flexible end portion the said plate extends laterally to the side edges 18 and 19 thereof, forming lateral side portions 20 and 21 which engage or are supported by the sole of the shoe.

Figure 2 is a longitudinal sectional view on the line 2—2 of Figure 1;

Fig. 3 is a plan view of the arch supporting means;

For the purpose of providing adjustability in the height of the plate 10 at a plurality of points above the sole of the shoe the said plate is rigidly affixed adjacent each of its lateral edges to a flanged interiorly threaded tubular member 22 by rivets 23 or other securing means, the tubular portion 24 thereof being slidable for movement toward and from the shoe sole, in a guide sleeve 25 secured in an opening 26 extending through the sole of the shoe. A screw 27 having a flanged head 28 is arranged against the lower end 29 of each of the guide sleeves 25 with its threaded shank 30 engaging the interiorly threaded opening 31 of the said tubular member 22. The screw 27 is held in operative position for turning movement, against the lower end of each of the guide sleeves 25, by an outer plate 31, preferably arranged in a recess in the outer face of the shoe sole, and secured in position therein by rivets 32 or other securing means passing through the sole of the shoe and through a plurality of leaf spring plates 33 arranged in superposed position adjacent the side edge of the shoe. It is to be understood that one such plurality of leaf spring plates is arranged adjacent each side edge of the shoe and which operates to take the weight of the wearer thrust upon the supporting plates and to distribute such weight over the area of the shoe sole supporting the leaf spring plates.

The said leaf plates are arranged in superimposed relation, each plate tapering in thickness from the point of attachment with the guide sleeve towards its outer ends, and each of the upper plates being relatively shorter than the plate beneath to provide a stepped arrangement at each end. As shown in the drawing, the said plates are three in number under the inner longitudinal arch and two in number under the outer longitudinal arch, but are not necessarily limited to such numbers, as the plates may consist of two or more at each side edge, or of the lowermost plate only. The lowermost leaf plates may be made integral by means of a connecting link or the said plates may be connected by a tie plate 35 which is provided with an opening 36 at each end for engagement with the guide sleeves 25 to provide a rigid construction for holding the said guide sleeves in position, thereby preventing spreading apart of the guide sleeves or lateral displacement thereof. As hereinbefore explained, the said leaf plates take up the weight thrust upon the arch support and for this purpose the guide sleeves are crimped or riveted at their upper ends against the upper faces of the topmost leaf plates as at 36.

Preferably, the inner sole of the shoe is recessed adjacent each side edge thereof to receive the said leaf plates and in order that the leaf plates may be free to flex and bend with the movement of the shoe sole a flat

plate 37 is arranged in the said recess beneath the forward end of the lowermost leaf, on which the said leaf plate has a freely sliding movement. This plate 37 may be secured in position by means of nails 38 and if desired the same may be provided with integral projections 39 adapted to be embedded in the sole of the shoe.

As shown in Figure 1, the arch supporting plate is also provided with a similar adjusting means arranged under the bones of the foot forming the metatarsal arch, or, in other words, substantially under the ball of the foot, whereby the forward end of the arch supporting plate may be adjusted in height above the insole of the shoe. The forward end of the said arch supporting plate is supported to freely slide upon a leather pad secured to an oval shaped plate 40 which is slotted as at 41 to provide a relatively flexible rim portion 42, and centrally of the said rim portion is provided with a plurality of openings 43 for engagement with an upstanding stud 44 of a flanged tubular member 45. This tubular member is slidably mounted in a flanged guide sleeve 46 which latter member is arranged in an opening in the sole of the shoe and secured in position therein by means of rivets 47 which engage an outer plate 48 and hold a flanged screw 49 in position against the lower end of the guide sleeve, similar to the arrangement and construction for holding the screws 27 in position against the guide sleeves 25.

The said leaf plates 33 are preferably arched to conform to the arch of the inner sole of the shoe in the region of the instep, and in order that said plates will flex and bend with the movement of the shoe sole they are preferably made of spring metal. Between said leaf plates and the arched supporting plate a leather insole 50 is provided which forms a cushion between the said metal plates.

Another leather insole 52 may be arranged upon the arch supporting plate 10 as shown in Figs. 2 and 8, and this insole may be made co-extensive with the whole insole of the shoe. The said insole 52 may be secured to the plate 10 by rivets 53 passing through the said insole, the said plate, and the flange of the tubular extension 22.

The guide sleeves 25 have their upper ends recessed forming annular shoulders 51 which underlie the lowermost leaf of the spring leaf plates 33. The crimping of the upper ends of the said guide sleeves against the upper faces of the topmost leaf plates securely holds the spring leaf plates in the recesses in the said guide sleeves between the crimped edges 36 and the shoulders 51.

Having described my invention, I now claim:

1. The combination of a shoe and a plate for supporting the arch of the wearer, spring

leaf plates arranged on the insole of the shoe, and means secured to the arch plate and connected to the spring leaf plates supporting said arch plate in spaced relation above the 5 said spring leaf plates.

2. The combination of a shoe and an arch support including an arch plate, a plurality of spring leaf plates arranged in superimposed position on the insole of the shoe, and 10 means secured to the arch plate and connected to the spring leaf plates, supporting the arch plate in spaced relation above the spring leaf plates.

3. The combination of a shoe and an arch support including an arch plate supporting the arch of the wearer, a plurality of spring leaf plates arranged in superimposed position on the insole of the shoe, and means secured to the said arch plate and adjustably 20 connected to said spring leaf plates for fixedly supporting the said arch plate and for adjustably regulating the height of the arch plate above the spring leaf plates.

4. The combination of a shoe and an arch support including an arch plate for supporting the arch of the wearer, spring leaf plates arranged in superimposed relation on the insole of the shoe at each side edge thereof, and means arranged between the said arch plate and the spring leaf plates, adjacent each lateral edge of the arch plate, for supporting said arch plate.

5. The combination of a shoe and an arch support including an arch plate for supporting the arch of the wearer, spring leaf plates arranged in superimposed relation on the insole of the shoe at each side edge thereof, and adjustable means secured to said arch plate adjacent each lateral edge thereof movably 40 connected to the said spring leaf plates for adjustably supporting the said arch above the insole of the shoe.

6. The combination of a shoe and an arch support including an arch plate for supporting the arch of the wearer, a plate arranged on the insole of the shoe having its side edges conforming to the marginal portions of the shoe sole at the shank portion, and means 50 adjacent each lateral edge of the arch support plate operatively connected to the second named plate for supporting said arch support plate in position in the shoe.

7. An arch support adapted to be applied 55 to a shoe for supporting the arch of the wearer, including an arch plate, a plurality of spring leaf plates arranged on the insole of the shoe adjacent each lateral edge thereof in the region of the shank, said leaf plates tapering in thickness towards their outer ends, and the uppermost plate being relatively 60 shorter than the plate beneath, providing a stepped arrangement at each end, and means operatively connecting the arch plate to said 65 supporting plates adjacent each lateral edge

thereof for supporting the arch plate above the insole of the shoe.

8. An arch support adapted to be applied to a shoe for supporting the arch of the wearer, including an arch plate, a plurality of 70 spring leaf plates arranged on the insole of the shoe adjacent each lateral edge thereof in the region of the shank, said leaf plates tapering in thickness toward their outer ends, and means operatively connecting the arch plate to said supporting plates adjacent each lateral edge thereof for supporting the arch plate above the insole of the shoe.

9. An arch support adapted to be applied to a shoe for supporting the arch of the wearer, including an arch plate, a plurality of 80 spring leaf plates arranged on the insole of the shoe adjacent each lateral edge thereof in the region of the shank, and the uppermost plate being relatively shorter than the plate beneath, providing a stepped arrangement at each end, and means operatively connecting the arch plate to said supporting plates adjacent each lateral edge thereof for supporting the arch plate above the insole of the 85 shoe.

10. An arch support adapted to be applied to a shoe for supporting the arch of the wearer, including an arch plate, a plurality of 90 spring leaf plates arranged on the insole of the shoe adjacent each lateral edge thereof in the region of the shank, said leaf plates tapering in thickness toward their outer ends and conforming at their side edges to the shape of the shank of the shoe, and the uppermost plate being relatively shorter than the plate beneath, providing a stepped arrangement at each end, and means operatively connecting the arch plate to said supporting plates adjacent each lateral edge thereof for supporting the arch plate above the insole of the 95 shoe.

11. An arch support adapted to be applied to a shoe for supporting the arch of the wearer, including an arch plate, a tubular member threaded interiorly and secured to said plate adjacent a side edge thereof, spring leaf plates adapted to be secured in superimposed relation on the insole of the shoe, a second tubular member adapted to be arranged in the insole of the shoe and secured to the said spring leaf plates in which the said first mentioned tubular member is slid able, and means arranged against the outer end of the second mentioned tubular member operatively 110 engaging the first mentioned tubular member for adjusting the height of the arch plate 115 above the sole of the shoe.
